US00D669754S

(12) **United States Design Patent**
Wackwitz(10) **Patent No.:** **US D669,754 S**
(45) **Date of Patent:** **** Oct. 30, 2012**(54) **ACCESSORY**(75) Inventor: **Jeffrey M. Wackwitz**, Waukesha, WI
(US)(73) Assignee: **Milwaukee Electric Tool Corporation**,
Brookfield, WI (US)(**) Term: **14 Years**(21) Appl. No.: **29/388,254**(22) Filed: **Mar. 25, 2011**

FIG. 1 is a perspective view of an accessory, such as a sanding pad, having a tool interface.

FIG. 2 is a top view of the accessory shown in FIG. 1.

FIG. 3 is a bottom view of the accessory shown in FIG. 1.

FIG. 4 is a rear view of the accessory shown in FIG. 1.

FIG. 5 is a front view of the accessory shown in FIG. 1.

FIG. 6 is a right side view of the accessory shown in FIG. 1; and,

FIG. 7 is a left side view of the accessory shown in FIG. 1.
